CAGE FOR DOMESTIC ANIMALS

Gerald Dennis Hutchings, Peterborough, England, assignor to R. H. Pollard (Flora & Sundries) Limited, Peterborough, England, a British company

Filed Sept. 18, 1967, Ser. No. 8,612

Term of patent 3½ years

(Cl. D30—1)

Fig. 1.

Fig. 2.

Fig. 3.

Fig.4

Fig.5

FIGURE 1 is an elevational view of one side of the cage for domestic animals showing my new design;

FIGURE 2 is an elevational view of one end of the cage;

FIGURE 3 is an elevational view of the opposite end of the cage;

FIGURE 4 is a plan view of the cage; and,

FIGURE 5 is a sectional view of the cage as seen in the direction of the arrows on the line 5—5 in FIGURE 4.

I claim:

The ornamental design for a cage for domestic animals, substantially as shown.
